VALVE BAG FILLER

Martin J. Miller, Bellefonte, Pa.

Application June 9, 1933, Serial No. 675,131

5 Claims. (Cl. 226—48)

This invention relates to improvements in devices for filling bags, and more particularly to devices for filling valve bags of the type usually employed in the handling of fine dry material such as hydrated lime, cement, ground limestone, flour and the like.

In accordance with the present invention a filling device of the character above suggested is provided whereby air under pressure is used for forcing the material into the bag to be filled, and also for cleaning the filling nozzle of the device subsequent to each bag filling operation.

Further the invention comprehends the provision of a bag filling device having means incorporated therein for automatically shutting off the flow of air each time a bag has been filled.

Further it is an object of the present invention to provide a bag filling device which is simple and economical in construction and thoroughly practical and efficient in operation.

The invention together with its numerous objects and advantages will be best understood from a study of the following description taken in connection with the accompanying drawings wherein is illustrated a preferred embodiment of the invention.

It is to be understood at the outset that it is in no wise intended to restrict the invention to the precise details of construction, combination and arrangement of elements as shown in the practical embodiments herein illustrated, other than may be necessary to meet the requirements of the prior art and scope of the appended claims.

In the drawings:

Figure 1 is a side elevational view of the bag filling device with the parts in position during a bag filling operation.

Figure 2 is a fragmentary vertical sectional view through an upper portion of the filling device.

Figure 3 is a fragmentary sectional view of the outlet end of the air nozzle.

Figure 4 is a transverse sectional view through the filling nozzle.

Figure 5 is a top plan view of the device.

Figure 6 is a horizontal sectional view taken substantially on the line 6—6 of Figure 1.

Figure 7 is a sectional view through a three way valve.

Figure 8 is a vertical sectional elevational view taken substantially on the line 8—8 of Figure 1.

Figure 9 is a perspective view showing the upper portion of one of the uprights of the supporting frame.

Figure 10 is a perspective view of the lug equipped portion of the valve operating handle.

Figure 11 is a perspective view of a link to be hereinafter more fully referred to.

Referring to the drawings by reference numerals it will be seen that the device comprises a supporting structure including a base 1 having rising therefrom pairs of standards 2 and 3 respectively. Suitably supported on the upper end of the standards 2 and 3 is a hopper 4 that adjacent its bottom is provided with a discharge outlet 5 to which is connected through the medium of a flexible sleeve 6 a filling nozzle 7. Mounted on a wall of the hopper 4 opposite to the outlet 5 is a coupling 8 to the inner end of which is suitably connected an air nozzle 9. To the outer end of the coupling 8 is suitably connected one end of an air pipe 10 that leads from a suitable source of supply. The air pipe 10 is braced with respect to the hopper 4 and the standards 2 through the medium of suitable braces 11. Arranged within the air pipe 10 is a three way valve 12 the core of which is provided with a crank or handle 13 to one end of which is pivotally connected a control handle 14. Control handle 14 operates in a suitable guide 15 provided therefor on one of the standards 3. Suitably connected with the handle 14 is a spring 16 that is anchored to one of the brace rods 11 and normally urges the crank handle 13 to rotate in clockwise direction for closing the valve 12.

Means is provided for automatically releasing the handle 14 to operate the valve 12 for shutting off the flow of air to the nozzle 9 when a bag has been filled. To this end, there is provided a frame structure that embodies a platform 17 having rising therefrom bars or posts 18 braced with respect to the platform by braces 19. The upper ends of the posts or bars 18 are adjustably connected with post or bar sections 20 through the medium of bolt and slot means 21. A second pair of bars disposed rearwardly of the bars 18 and designated by the reference numeral 22 are connected at their lower ends to the platform 17, and at their upper ends have angularly disposed portions suitably secured to the upper ends of the bars 20. The bars 22, as are also the bars 20 are disposed at opposite sides of the nozzle, and the bars 22 adjacent their upper ends are connected, above and below nozzle 7, by straps 23 that engage the nozzle in a manner clearly shown in Figure 2.

Adjacent their upper ends the bars 20 are pivotally connected with lugs 24 provided on one

wall of the hopper 4 through the medium of links 25. The platform 17 at its rear edge has secured thereto rods 26, the free ends of which are formed to engage selected apertures 27 arranged in vertical series on the lower portions of the standards 3. One of the rods 22 is provided adjacent its upper end with a keeper plate 28 with which is engageable a lug 29 provided on the handle 14 for retaining the handle 14 projected against the action of spring 16 during the filling of the valve bag 30.

Each of the bars 20 adjacent its lower portion has pivoted thereto one end of a lever 31 that is pivoted intermediate its ends as at 32 to a standard 3. On the free ends of the levers 31 are adjustable weights 33. The weights 33 can be adjusted as desired for retaining the platform 17 normally in a horizontal position. Also, by adjusting the bars 18 relative to the bars 20 platform 17 may be raised or lowered with respect to the nozzle 7.

Referring again to the nozzle 7 it will be seen that the same adjacent its outlet end has integral therewith an air passage 34 that terminates at the small end of the nozzle. The passage 34 has an end 35 suitably connected with one end of a flexible conduit tube 36 which is also connected to a dust bag 37. Adjacent the end 35 thereof passage 34 has extending therefrom a nipple 38 to which is coupled one end of a flexible air tube 39 that in turn is connected to the outlet port 40 of the casing of valve 12. As will be noted, a second port 41 of the valve is connected to the pipe 10, while the third port 42 of the valve is connected with the coupling 8 for establishing communication between the air pipe 10 and the nozzle 9.

The operation of the device is thought apparent from the foregoing, however it may be briefly explained as follows:

After all adjustments have been made the valve bag 30 has its valve equipped and suitably engaged with the nozzle 7, while the material to be fed to the bag is placed within the hopper 4. The handle 14 is then pulled against the action of spring 16 for engaging the lug 29 associated with the handle behind the plate 28 associated with one of the bars 22 as shown in Figure 2. The valve 12 is thus actuated for placing the core thereof in the position shown in Figure 7 to establish communication between the air pipe 10 and the nozzle 9. Thus it will be seen that air under pressure will pass through the valve to discharge through the perforations at the end of the nozzle 9 for creating a suction at the outlet 5 of the hopper. The suction thus created draws the material from the hopper through the outlet 5, and the material under pressure is forced through the nozzle 7 into the bag 30.

When the bag 30 becomes filled the weight thereof on the platform 17 will cause the platform 17 and associated parts to move downwardly thus moving the plate 28 out of the path of the lugs 29 and permitting the handle 14 to move to the left in Figure 1 thus rotating the core of the valve 12 in a clockwise direction (see Figures 1 and 7) for shutting off the flow of air to the nozzle 9 and for establishing sufficient communication between ports 40, 41 of the valve to permit a certain amount of air under pressure to pass through the hose or tube 39 for blowing out passage 34, to clean the passage and place the nozzle in clean condition for the next operation. The flexible hose connection 6 between the outlet 5 and nozzle 7 will of course permit angular move-

ment of the nozzle 7 relative to the outlet 5 upon the downward movement of platform 7 and its associated parts.

It will also be apparent, that during the filling of the bag 30, dust resulting therefrom will be drawn through the passage 34 and the tube 36 into the dust collecting bag 37. Also, when the valve 12 is operated in the manner just explained for directing air through the hose or tube 39, such air passing through the passage 34 will create a suction at the outlet end of the nozzle sufficient for removing any accumulations that might otherwise tend to clog up the discharge end of the nozzle 7.

After a bag has been filled, the same is removed, after which the proper adjustments are then made and the next bag is placed on the platform 17 with the valve end thereof properly engaged with the nozzle 7. In this connection it will be noted after the filled bag has been removed from the platform 17, the same will move upwardly to its normal position under influence of the weights 33 on the levers 31.

Having thus described my invention, what I claim as new is:

1. In a bag filling device, a supporting structure, a hopper mounted on said supporting structure and provided with an outlet, a nozzle, a flexible connection between said nozzle and said outlet, valve controlled means for forcing air through said outlet and said nozzle including an air jet arranged within said hopper in operative position to said outlet, and a valve connected with said jet, an operating rod pivotally connected with said valve, spring means engaging said rod normally urging the same to move in one direction, guide means for the rod mounted on the supporting structure, a bag supporting platform, means for suspending said platform in a manner for vertical movement, and including weight means for normally retaining the platform in an elevated position, a lug on said valve actuating member, and a member arranged in the path of the lug and movable with the platform for releasing the valve actuating member upon downward movement of said platform.

2. In a device of the character described, a hopper provided with an outlet, a nozzle connected with said outlet, an air tube integral with said nozzle and terminating at one end at the discharge end of the nozzle, an air nozzle arranged in said hopper in operative position to said outlet, an air conduit connected with said nozzle, a three way valve in said conduit, a flexible tube connecting one end of the air tube associated with the nozzle with one side of said valve, and means for operating said valve for directing the air selectively to the air nozzle or to the aforementioned air tube associated with the first named nozzle.

3. In a device of the character described, a hopper provided with an outlet, a nozzle connected with said outlet an air tube integral with said nozzle and terminating at one end at the discharge end of the nozzle, an air nozzle arranged in said hopper in operative position to said outlet, an air conduit connected with said nozzle, a three way valve in said conduit, a flexible tube connecting one end of the air tube associated with the nozzle with one side of said valve, and means for operating said valve for directing the air selectively to the air nozzle or to the aforementioned air tube associated with the first named nozzle, a dust bag, and a hose connection between said dust bag and the aforementioned air tube.

4. In a bag filling machine, the combination of hopper having a discharge nozzle, said nozzle including an air tube extending substantially longitudinally thereof externally of the nozzle, air blast means terminating within the hopper in substantial alinement with the nozzle, and including a three way valve for controlling the same, a conduit connecting one part of said valve with the air tube, and mechanism for operating 10 said valve.

5. In a device of the character described, in combination, a hopper, a nozzle for said hopper provided externally with an air tube, said tube extending substantially longitudinally of the nozzle and terminating at one end adjacent the discharge end of the nozzle, a conduit tube connected with the said air tube intermediate the ends of the latter, and air blast means connected with the air tube at the end of the tube remote 80 from the discharge end of the nozzle.

5. In a device of the character described, in
